HEEL CONSTRUCTION FOR SHOES

George E. Musebeck, Danville, Ill., assignor to
 Musebeck Shoe Company, Danville, Ill., a corporation

Application April 10, 1943, Serial No. 482,523

7 Claims. (Cl. 12—147)

This invention relates to a heel construction for shoes and the method of producing heel structures. The invention is directed toward effecting economy in the use of sole leather and the cost of production of shoes, while at the same time providing a more rigid and secure heel support. This is accomplished by providing a hollow outsole heel extension in which a composition sealing filler is compressed which acts as a bonding or vulcanizing agent between the heel seat and base.

The advantages of this construction, as well as the method of producing the same will be more readily apparent from the following specification and the attached drawing.

The full nature of the invention will be understood from the accompanying drawing and the following description and claims:

Fig. 1 is a bottom view of a shoe in process of construction showing it before mounting the heel. Fig. 2 is a section taken on the line 2—2 of Fig. 1, with parts broken away. Fig. 3 is an enlarged bottom view of the heel seat before the heel base is mounted thereon. Fig. 4 is a section taken on the line 4—4 of Fig. 3. Fig. 5 is the same as Fig. 2, showing the completed heel construction.

In the drawing there is shown by way of illustration a shoe having an outsole 10 which is cut so as to terminate at substantially the heel breast line. The heel seat includes the usual insole 12 and may embody therein the rear end of a metal shank stiffener 13 as disclosed in my Letters Patent No. 2,290,988, issued July 28, 1942, entitled "Process of forming welt shoes." In the usual manner the upper 14 is tacked about the heel seat.

By way of economy in sole leather and cost, particularly in the larger size shoes, the outsole 10 is so cut that it extends only to the heel breast line with the cut end thereof extending transversely and beveled about five-eighths of an inch so that the free edge merges into the surface of the heel seat, as indicated at 15. This beveled portion is then tacked down by the tacks 16.

To provide the necessary outsole heel extension for receiving the heel base, a horseshoe-like lift 17 is cut from scrap sole leather in one or more parts. This piece is of the required thickness and shape to provide the sole extension. It takes a horseshoe shape so that it surrounds the recess indicated at 18 and if formed in two parts may be spliced at 19. Its free ends are beveled to conform with the bevel 15 so as to overlap and be spliced to that portion of the sole. This heel extension piece is then tacked to the heel seat

at 20, thereby providing an outsole heel extension having an internal recess 18.

This recess is packed with a plastic filling material adapted to harden, as indicated by the stippling in the recess 18. The material preferably employed is sawdust ground to about the consistency of cornmeal, mixed with an adhesive, such as pyroxylin cement used in other steps in shoe making and known as "Compo." This material when hardened provides a rigid structure similar in strength and rigidity to solid wood. The filler is packed into the recess so as to more than fill it, with some bulging beyond the plane of the heel piece 17 so that when compressed 10 therein while still in a plastic condition, it will be extruded around and under the heel piece, the end of the sole and the lapped upper 14. Thus, when compressed and hardened, it provides an interlocking sealing bond between the various parts of the heel structure, as well as a strengthening support and filler.

After the recess 18 has been packed with the filler, and while it is still in a plastic state, the heel base 21 is applied and nailed to the heel piece under sufficient pressure to compress the filler to the required density while causing it to spread and interlock with the parts of the heel 25 in a sealing and bonding relation.

The spliced joint between the sole and the heel piece 17 is preferably secured together by furniture glue, in addition to being tacked at 20, which, by reason of the bonding of said piece, acts to firmly support and interlock the end of the sole such as to provide an exceptionally strong joint 30 at the heel breast line. However, the main advantage as will be observed from the foregoing, lies in the fact that it is not necessary to obtain full length sole leathers, particularly of the larger sizes, to extend over the heel seat. Such sole leather as is cut at the heel breast line may be 35 otherwise used at a saving in cost, while the heel lift provided by the scrap piece or pieces, as at 17, involves little or no expense compared with the saving in the sole leather. However, beyond such economy in production, by reason of the 40 recess formed in the heel and the strengthening and bonding filler therein, all parts of the heel structure, including the heel base, the adjacent end of the sole, the insole, and the overlapping upper, will be bonded to structurally form a 45 stronger heel.

The invention claimed is:

1. The method of attaching a heel to a shoe having an outsole and heel seat, consisting in securing a supporting and confining strip about the periphery of the heel seat to provide a heel lift

having an enclosed recess, packing a bonding and sealer filler composition in said recess, and securing a heel piece over the heel lift and filler under pressure to compress and confine said filler within said recess while in a plastic state to effect an interlocking sealing bond with the assembled parts of the heel structure.

2. The method of attaching a heel to a shoe having an outsole and heel seat consisting in securing a supporting and confining strip about the periphery of the heel seat to provide a heel lift having an enclosed recess securing the free ends of said strip to the adjacent end of the outsole at the heel breast line, packing a bonding and sealer filler composition in said recess and securing a heel base over the heel lift and filler under pressure to compress and confine said filler within said recess while in a plastic state to effect an interlocking sealing bond with the assembled parts of the heel structure.

3. The method of attaching a heel to a shoe having an outsole and heel seat, said outsole terminating at the heel breast line with a beveled surface feathered to the heel seat, consisting in securing a U-shaped scrap leather strip about the periphery of the heel seat to provide a heel lift having an enclosed recess, tapering and securing the free ends of said strip in overlapping relation to the adjacent end of the outsole, packing a bonding and sealer filler of a finely divided wood composition in said recess, and securing a sole base over the heel lift and filler under sufficient pressure to compress and confine said plastic filler within said recess while in a plastic state to effect an interlocking sealing bond with the assembled parts of the heel structure.

4. A heel construction for shoes, in combination with an outsole terminating substantially at the breast line of the heel seat, of a heel lift comprising a curved strip extending about the heel seat with its free ends joined to the end of the outsole to provide an enclosed recess, a filler comprising a bonding and sealing compound packed into said recess, and a heel base secured to said heel lift in compressing relation to said filler for confining said filler within the recess under such

pressure as to effect a bonding and sealing engagement with the heel structure.

5. A heel construction for shoes, in combination with an outsole terminating substantially at the breast line of the heel seat, of a heel lift comprising a curved strip extending about said heel seat with its free ends joined to the end of the outsole to provide an enclosed recess, a filler comprising a bonding and sealing compound consisting of finely divided wood particles mixed with pyroxylin cement, a heel base adapted to fit over and enclose said filler within said recess, and means for securing said heel base to the heel lift with the filler compound under compression to effect a bonding and sealing engagement with the heel structure.

6. A heel construction for shoes, in combination with a leather outsole terminating substantially at the breast line of the heel seat with a beveled edge, of a heel lift comprising a U-shaped leather strip extending about and secured to said heel seat with its free ends beveled and overlapping the beveled portion of said outsole, a binder comprising a bonding and sealing compound pressed within the U-shaped strip to effect a bonding and sealing engagement between said strip, outsole and heel seat, and a heel base secured to said heel lift and filler and extending over the beveled portion of said outsole.

7. A heel construction for shoes, in combination with a leather outsole terminating substantially at the breast line of the heel seat with a beveled edge, of a heel lift comprising a U-shaped leather strip extending about the periphery of the heel seat formed with beveled edges conforming to and overlapping the beveled edge of the outsole to provide an enclosed recess, a filler comprising saw dust mixed with pyroxylin cement packed within said recess to overlap the beveled portion of said outsole, a leather heel base fitted over the beveled portion of the heel sole and said heel lift to enclose said filler, and means for securing said heel base to the heel lift with the filler compressed thereby to provide an interlocking bond and seal with the above-mentioned parts of the heel structure.

GEORGE E. MUSEBECK.
